UNITED STATES PATENT OFFICE

2,480,675

HEAT EXCHANGE UNIT

Joe C. Shaw and William J. Schlapman, Racine,
Wis., assignors to Young Radiator Company, a
corporation of Wisconsin

Application October 29, 1943, Serial No. 508,104

3 Claims. (Cl. 257—128)

1

This invention relates to a heat exchange unit where the heat exchange between a cooling medium and a coolant is effected by passing the cooling medium through a bundle of tubes around and between which is formed a core for the circulation of the coolant. More particularly, this invention relates to a heat exchange unit for aircraft engines where the cooling medium is air forced through the tubes and the coolant is lubricating oil circulated through the engine. Even more specifically, the invention relates to special improvements in the construction and arrangement of heat exchange devices of the type which comprises a cylindrical casing housing a bundle of cylindrical tubes whose hexagonal expanded ends space the tubes apart throughout almost their entire length and permit the bonding together of the ends so as to constitute the space between the tubes into a sealed core through which the oil circulates.

In modern aircraft, it is essential to superior operation of the engine to keep the lubricating oil as nearly as possible at a uniform temperature. Such uniform temperature must be maintained regardless of the extremely varying temperatures around and above the earth's surface where aircraft are used. The possibility of accomplishing that uniform temperature demands a cooling device wherein the degree of heat exchange exposure of the cooling medium and the coolant may be varied so as to compensate for the over-all conditions of weather and engine operation.

The main objects of this invention, therefore, are to provide an improved heat exchange unit of the type herein designated providing the highest possible degree of heat exchange exposure of the cooling medium and the coolant; to provide an improved construction of a warm-up chamber in the middle area of the unit; to provide an improved spacing arrangement of the air-flow tubes at strategic portions of the unit so as to accelerate the influence of the heat from the oil in the warm-up chamber when it tends to become congealed or highly viscous in the area surrounding the air flow tubes; to provide an improved construction of a heat exchange unit of this type which permits a more effective and economic manufacture of the several parts, which insures a more facile and efficient operation of the unit, and which has a greater capacity and durability than heat exchange units of this type heretofore provided.

In the particular embodiment of this invention herein shown:

2

Fig. 1 is a front elevation of the improved structure. The figure details only a portion of the tubes which fill the entire space within the shell;

5 Fig. 2 is a plan view illustrating the arrangement of the ports and channels through which the flow of oil into and out of the heat exchange unit is directed under the influence of appropriate valve mechanism;

10 Fig. 3 is a side elevation showing, in dotted outline throughout the greater portion of the view, the interior arrangement of the tubes of the warm-up chamber and the baffle plates. A portion of the figure is broken away at the lower right hand corner to illustrate how provision is made for communication between the bottom of the warm-up chamber and the core surrounding the adjacent air-flow tubes;

15 Fig. 4 is an enlarged fragmentary cross-sectional view taken on the line 4—4 of Fig. 1;

20 Fig. 5 is a similar view taken on the line 5—5 of Fig. 1;

Fig. 6 is an enlarged fragmentary transverse view taken on the line 6—6 of Fig. 1;

25 Fig. 7 is likewise an enlarged cross-sectional view taken on the line 7—7 of Fig. 6;

Fig. 8 is an enlarged fragmentary view taken on the line 8—8 of Fig. 3;

30 Fig. 9 is a plan view of one of the corrugated baffle plates such as used in the assembly shown in Fig. 10;

Fig. 10 is a view similar to Fig. 1 showing the use of corrugated baffle plates other than flat plates, as used in the structure shown in Fig. 1; 35 and

Fig. 11 is a plan view of one of the flat baffle plates.

In the particular embodiment of this invention shown in these several views, a supporting shell 40 or housing 9 is provided with a middle axially-disposed warm-up chamber 10 upon opposite sides of which are arranged symmetrically formed complementary heat exchange sections 11. These several parts are so arranged so that 45 there is intercommunication between the warm-up chamber and the cores of the sections 11 and between channels and ports formed in the valve base 12 whereby a valve mechanism (not shown) may regulate the relative flow of oil through the warm-up chamber and the cores of the heat exchange sections 11 in the passage of the oil between the engine and oil supply tank.

The shell 9, as will be observed, is a single piece of sheet metal having the ends welded together as shown at 13 so as to form a cylindri-

cal housing. At points on the exterior, lugs 14 are formed to permit the mounting of the unit in its proper place on the aircraft or other device with which it is intended to be used.

One of the principal features of this invention is the location and the structural form of the warm-up chamber 10 axially-disposed across the middle portion of the shell 9. This warm-up chamber comprises a pair of headers 15, a series of tubes 16 with which are associated the 10 baffle-supporting bars 17, and the end plates or closures 18 (see Figs. 6 and 7).

The headers 15 are secured, preferably by silver soldering, to the inner surface of the shell 9 at diametrically opposite points and between 15 which are positioned the tubes 16 and the end plates or closures 18. The baffle-supporting bars 17 are spanned between and secured to the end plates or closures 18. These headers, as is more clearly shown in Fig. 8, are of arcuate cross section, but have their ends expanded to a polygonal form. Openings 19 are formed in the sides of the lower header 15 at one end to provide communication between the warm-up chamber 10 and the adjacent portion of the cores of 20 the tube sections 11, as will be more clearly hereinafter pointed out. Auxiliary openings 19.1 (see Fig. 3) are similarly arranged at the opposite end of the lower header 15.

The tubes 16 are of elliptical cross-section. In 30 this embodiment six of them are aligned axially of the shell in the direction of their greatest dimension. The ends of these tubes are inserted through suitable openings in the headers 15 and are preferably silver soldered thereto. These 35 tubes 16 are also inserted through suitable openings in the baffle-supporting bars 17, and may or may not be silver-soldered thereto. The bars 17 are of U-shaped cross section and at their ends are silver-soldered to the end plates or closures 18. Ports 20 are formed in the lower ends of the first two (viewing Fig. 3 from the right) of the tubes 16 to afford communication between these two tubes and the adjacent portion of the cores of the tube sections 11 in advance of the communication provided through the ports or openings 19 in the lower head 15. The combined area of the openings 19 and 20 should be substantially equal to the combined area of the first three tubes 16. At other points the tubes 16 have orifices 21 formed therein registering with enlargements in the core of the sections 11 as will be more fully hereinafter pointed out.

A partition 22 (see Fig. 3) is formed in the upper header 15 so as to separate the six tubes at their upper ends into two batteries of three each. This partition 22 is related to compartments in the valve base 12, as will be more clearly hereinafter pointed out, so that the three tubes 16 to the right of Fig. 3 constitute a battery for the inflow of oil and the three tubes to the left constitute an outflow battery. The travel of the oil is indicated by dotted single-headed arrows.

Each air-flow heat exchange section 11 in general comprises the conventional arrangement of tubes 23 for this type of heat exchange unit. Each section is made up in a jig. The jigs are symmetrical and complement each other so that the sections 11 when finished are complementary symmetrical pairs, any two of which will fit in any previously constructed shell. Such forming of the sections as compared with the former

practice of assembling the tubes 23 in the shell is a tremendous advantage in manufacture.

As is generally practiced in the manufacture of this type of heat exchange units, the cylindrical tubes 23 have their ends expanded hexagonally so that a bundle of them may be assembled within almost any perimetric boundary. The hexagonal heads hold the tubes in spaced relationship thus forming a core around and between the tubes. The ends of these hexagonal enlargements are bonded together so as to seal the core within which oil may be circulated for exposing it to the heat exchange effected by forcing air through the tubes 23.

As is customary in this type of structure a series of baffle plates 24 are interposed at intervals and adjacent plates are provided with suitable openings 24.1, at opposite axial ends so as to cause the oil to follow a circuitous path in its passage through the core, as indicated by the double-headed dotted arrows shown in Fig. 3. These baffle plates also have orifices 24.2 (as shown in Figs. 4 and 9) formed in the middle area and the end opposite the main opening 24.1. The orifices permit a trickling through of the inflowing warmer oil from the under side of the baffle plates to the enlarged core space directly above the baffle plates. Figure 1 shows how the angled end flanges on the baffle plates 24 rest against the inner face of the shell 9. Figure 8 shows how the opposite end flanges engage the supporting cross-bars 17.

The baffle plates 24 may be either flat, as shown in Figs. 1 and 11, or corrugated, as indicated in Figs. 9 and 10. When flat baffle plates are used the air tubes 23 adjacent the baffle plates require pentagonal-formed ends, as shown in Fig. 1, rather than hexagonal ends, as shown throughout the remainder of the assembly. Moreover, the tubes formed for use adjacent to the flat baffle plates may preferably have the pentagonal heads eccentrically positioned relative to the cylindrical parts of the air-flow tubes. This insures having the cylindrical portions spaced out of contact with the baffle plates.

When the corrugated baffle plates are used the hexagonal ends fit in the corrugations as shown in Fig. 10, and the air flow tubes are uniform throughout the assembly.

Another of the principal features of this invention involves the special spacing of the tubes adjacent to the baffle plates 24 and also the special spacing of a row of tubes intermediate the baffle plates, together with the omission of an occasional tube on the row of specially spaced tubes.

The special spacing of the tubes adjacent to the baffle plates 24 is accomplished by fixing a strip of metal 26 along upper edges of the baffle plates 24 (see especially Fig. 4) so that the adjacent above row of tubes is spaced away from the baffle plates a greater distance than would otherwise be accomplished without the spacing strips 26.

The special spacing of a row of tubes 23 intermediate the baffle plates 24 is accomplished by inserting corrugated strips 27 (Fig. 4) between the enlarged hexagonal heads of adjacent rows of tubes. This provides spaces 28 on opposite sides of an intermediate row of tubes somewhat greater than the space provided between the rows of tubes otherwise throughout the sections 11. Such an enlargement of the space transversely across the sections 11 at several levels tends to facilitate the flushing of the congealed or highly viscous oil in those portions of the core

as the warm and less viscous oil tends to trickle from the warm-up chamber 10 into adjacent portions of the core of the sections 11. In order to facilitate this flushing action in these enlarged core areas, the orifices 21, in the tubes 16 of the warm-up chamber 10, register with the adjacent ends of this enlarged spacing.

In the rows of increasingly-spaced tubes 23 one or more of the tubes is omitted at a certain point intermediate the warm-up chamber 10 and the shell 9. The opening is closed by a plug 28 so as to complete the sealing of the core. This occasional omission of a tube further helps to accelerate the flushing of the congealed or highly viscous oil from the core of the sections 11 under the circumstances above mentioned.

The valve base 12 is suitably secured, preferably by silver soldering, to the shell 9 in alignment with the warm-up chamber 10. Stud bolts 30 are set in the base to provide for the attachment of a suitable valve mechanism such, for example, as shown in the co-pending application, Ser. No. 510,336, filed November 15, 1943, patented June 26, 1945, No. 2,379,109, of Joe C. Shaw.

This valve base 12 has formed therein partitions 31 and 32 (see Figs. 2 and 3) which form chambers 33, 34, and 35 which communicate with the inlet port 36 and the outlet ports 37 and 38 respectively. These partitions 31 and 32 are so arranged that the chambers 33 and 34 register with the upper header 15 on opposite sides of the partition 22 whereas the chambers 35 communicate with the upper ends of the cores of the sections 11 on opposite sides of the contiguous header 15, at the left hand end of the casing 9 as view from Fig. 3.

The end plates 18, in the form of channel members, are essential to complete the sealing of the core sections 11 around the warm-up chamber 10, as will be most particularly noted from Fig. 6. These channel members extend from one of the headers 15 to the other and, as shown, may even engage the adjacent tubes 16. In order to provide for an accurate sealing of the enlarged ends of the tubes 23 along the members 18 alternate tubes have a cross-sectional form as shown at 39 of Figs. 1 and 7.

One of the incidental advantages of this arrangement of the warm-up chamber is the provision of the area 40 (see Figs. 6 and 7) vertically and transversely around the tubes 16 and connecting the cores of the two sections 11. The oil which congeals or becomes highly viscous in these areas is exposed to the heat of the oil as it begins to flow through the warm-up chamber 10 and is more readily converted into less viscous condition so as to coact with the enlarged spacing between the rows of tubes intermediate the baffle plates 24 and above the baffle plates to accelerate the flushing of the core in the two sections 11.

In explaining the operation of the device herein shown, when used with the lubricating oil system for an aircraft engine, it will be understood that a suitable valve mechanism, similar to that shown in the aforementioned copending application, would be provided to control the flow of oil through the inlet port 36 and out of one or the other of the outlet ports 37 and 38.

When the temperature of the oil entering the valve mechanism is sufficient to cause the thermostat to open communication to the port 36, oil would begin to flow in the direction of the single headed arrows shown in Figs. 2 and 3. This flow of oil would pass downwardly through the in-

flow battery of tubes 16, of the warm-up chamber 10, through the lower header 15 upwardly through the out-flow battery of tubes 16 to the upper header 15 and out through the outlet port 37, as indicated by the dotted single-headed arrows in Figs. 2 and 3.

It is assumed that the oil in the communicating cores of the tubular sections 11 is too nearly congealed or too viscous to flow when communication is first opened through the inlet port 36. That means that the only outlet is from the port 37.

The warm oil passing downwardly and upwardly through the tubes of the warm-up chamber 10 will first tend to warm up and reduce the viscosity of the oil in the space 40 around the elliptical tubes 16. Also, the oil will tend to trickle out through the openings 21 into the horizontally enlarged portions of the core on opposite sides 20 of the rows of tubes 23 intermediate the baffle plates 24. As the congealed or highly viscous oil in the enlarged horizontal areas of the core continues to warm up, it will soon reach the congealed or highly viscous oil in the space where the tubes 25 are omitted.

This trickling of the oil horizontally and axially through these enlarged core spaces will tend to accelerate the lowering of the viscosity of the oil in other portions of the core of the sections 11 preparatory to securing a movement of the oil 30 through these cores as soon as the valve mechanism acts to open the outlet port 38. This will occur as soon as the temperature of the oil passing out through the port 37 to the valve mechanism 35 affects the thermostatic control of the valve sufficiently to further actuate the valve mechanism.

The opening of the outlet port 38 means the simultaneous closing of the outlet port 37. Thereupon, oil entering through the right hand battery 40 of tubes 16 of the warm-up chamber 10 will flow out through the lower header openings 19 and the openings 20 in the lower ends of the tubes 16. This warmer oil then entering the lower portions of the cores of the tubular sections 11 will begin 45 to move up through the lowermost portions of these sections. The lowermost baffle plates 24 will deflect this flow axially toward one end of the shell 9. Inasmuch as the next adjacent baffle plate 24 will have its openings 24.1 at the opposite 50 end from the lowermost baffle plate the flow of oil in the portions between the two lowermost baffle plates will be directly axially toward the opposite end of the shell 9. Because adjacent plates have these openings 24.1 at opposite 55 ends, the flow of oil will follow a circuitous path through the unit, as indicated by the double-headed arrows in Fig. 3.

When this oil begins to flow out through the openings 19 into the lowermost portion of the tubular sections 11 the rising oil striking against the baffle plates 24 will be permitted to trickle through the orifices 24.2 into the enlarged core areas immediately above the baffle plate. Here, again, this will tend to facilitate the reducing 65 of the viscosity of the oil in the adjacent portions of the core and help to accelerate the flushing of any highly viscous oil remaining in the core in the sections 11.

Such a structure, providing these series of enlargements in the core areas of the tubular sections 11 along and intermediate the baffle plates, tends to increase very greatly the efficiency of this heat exchange device over previous structures of this type. With this structure it is possible 75 to secure a more sensitive and accelerated action

in the heat exchange (1) between the air passing through the tubes and the oil circulating in the surrounding cores and (2) between oil in the warm-up chamber and the cores of the tubular sections 11. This makes possible securing a 5 quicker and closer manipulation of the valve mechanism under the action of the thermostat as influenced by the oil passing through the unit. This is especially beneficial when it is necessary to start up the cooling system in the lower temperature conditions and when the aircraft has to alternate between the high temperature at the earth's surface and the low temperature of the stratosphere.

Variations and modifications in the details of 15 structure and arrangement of the parts may be resorted to within the spirit and coverage of the appended claims.

We claim:

1. In a heat-exchange unit of the class described, the combination of a supporting shell having an inlet and two separate outlet ports, conduit means providing an axially-disposed fluid flow path extending transversely across said shell and dividing said shell into two compartments, said conduit means communicating at one end with said shell inlet port and at the other end with one of said shell outlet ports, tubes extending axially of said shell and filling each of said compartments, said tubes having their ends supported in bonded relationship so as to form a sealed fluid core surrounding said tubes in each of said compartments, said cores communicating with the other of said shell outlet ports and with said transverse chamber at a point intermediate said inlet and said one outlet port, baffle means associated with said axially-disposed tubes in each of said compartments for causing a back-and-forth fluid flow through said fluid cores axially of said shell between the communication of said cores with said transverse conduit means and said other shell outlet port, and other means forming an extra spacing of an occasional row of said axially-disposed core-forming tubes extending from said transversely-disposed conduit means to the periphery of said shell thereby providing occasional enlargements of said fluid cores disposed axially of said shell parallel to said baffle means, the conduit means forming said axially-disposed fluid flow path having apertures formed therein in registration with said occasional core enlargements whereby fluid from said conduit means is admitted directly to said fluid core enlargements.

2. In a heat-exchange unit of the class described, the combination of a supporting shell having an inlet and two separate outlet ports, conduit means providing an axially-disposed fluid flow path extending transversely across said shell and dividing said shell into two compartments, said conduit means communicating at one end with said shell inlet port and at the other end with one of said shell outlet ports, tubes extending axially of said shell and filling each of said compartments, said tubes having their ends supported in bonded relationship so as to form a sealed fluid core surrounding said tubes in each of said compartments, said cores communicating with the other of said shell outlet ports and with said transverse conduit means at a point intermediate said inlet and said one outlet port, baffle means associated with said axially-disposed tubes in each of said compartments for causing a back-and-forth fluid flow through said fluid cores axially of said shell between the communication

of said cores with said transverse conduit means and said other shell outlet port, spacing strips along the ends of certain of said baffles extending from said conduit means to the periphery of said shell for spacing the contiguous row of axially-disposed core-forming tubes away from said baffles a distance greater than the normal spacing of said tubes to form core enlargements, and other means forming an extra spacing of an occasional row of said axially-disposed core-forming tubes intermediate certain of said baffle means extending from said conduit means to said periphery, said extra spacing strips and said other conduit means providing occasional enlargements of said fluid cores disposed axially of said shell parallel to said baffle conduit means, the means forming said axially-disposed fluid flow path having apertures formed therein in registration with said core enlargements along said baffles and said intermediate row of tubes whereby fluid from said conduit means is admitted directly to said fluid core enlargements.

3. A heat exchange unit of the class described comprising a supporting-shell, means defining a warm-up chamber, baffle means arranged in said shell axially thereof with the opening in one baffle-means located at the opposite end from that in adjacent baffle-means whereby the interior of said shell is formed into a tortuous fluid-flow 25 passage extending axially of said shell with one side of said passage contiguous to said warm-up chamber, a bundle of open-ended tubes disposed in rows parallel to said baffle means and uniformly spaced apart between adjacent baffle means so 30 as to establish a predetermined resistance to fluid flow through said tortuous shell passage, and means spacing apart adjacent rows of said tubes between at least one pair of adjacent baffles a distance greater than the otherwise uniform 35 spacing of said rows of tubes whereby the resistance to fluid flow between two adjacent rows of said tubes intermediate said baffle-means and parallel thereto is less than that established by said uniform spacing of said tubes between adjacent baffles said means defining said warm-up 40 chamber having apertures formed therein in registration with the more-than-uniformly spaced tubes effected by said spacing means whereby 45 fluid from said warm-up chamber defining-means 50 is admitted directly to the space between said rows of tubes.
